UNITED STATES PATENT OFFICE.

JOHN HEBERLING, OF ROCHESTER, NEW YORK, ASSIGNOR, BY DIRECT AND MESNE
ASSIGNMENTS, TO LORENZO G. MABBETT, OF ROCHESTER, NEW YORK.

BUCKLE.

1,087,012.

Specification of Letters Patent. Patented Feb. 10, 1914.

Application filed June 5, 1909. Serial No. 500,249.

To all whom it may concern:

Be it known that I, JOHN HEBERLING, of Rochester, in the county of Monroe and State of New York, have invented certain new and useful Improvements in Buckles; and I do hereby declare the following to be a full, clear, and exact description of the same, reference being had to the accompanying drawings, forming a part of this specification, and to the reference-numerals marked thereon.

The present invention relates to buckles designed for securing a rope or other similar article into the form of an adjustable loop which may be passed about the neck of a horse, the horns of cattle, a tree, a post, or in fact about anything which it is desired to secure or which is to be employed for holding or supporting another object, and it has for its object to provide a simple construction which is durable in use and inexpensive to manufacture.

To these and other ends the invention consists in certain improvements and combinations of parts all as will be hereinafter more fully described, the novel features being pointed out in the claims at the end of the specification.

In the drawings: Figure 1 is a view of the buckle with the rope attached thereto and formed into a loop; Fig. 2 is an enlarged view of the buckle with portions of the rope; Fig. 3 shows the buckle adjusted to receive the rope to form a loop; Fig. 4 is a section on the line *a—a* of Fig. 2, and Fig. 5 is a section on the line *b—b* of Fig. 2.

In the embodiment of the invention herein illustrated there is employed a frame or plate 1 having a slot 2 therein and means at one end of the slot permitting the attachment of the rope or other connection thereto; said means in this instance embodying an eye 4 on the frame through which one end of the rope 3 is passed and spliced or otherwise secured therein.

The slot 2 is adapted to have an intermediate portion 5 of the rope or connection 3 looped therethrough and in order to prevent the withdrawal of this loop and at the same time secure a binding action to prevent the rope slipping, there is employed a retaining device or tongue comprising preferably a cross piece 6 having a movement in a plane parallel with the plane of the frame 1 to bridge the slot at an intermediate point

so that the rope may lie upon opposite sides of the cross piece in the manner shown in Fig. 4. Preferably the movement of the cross piece is effected by turning the latter about an axis perpendicular to the plane of the frame 1 and to this end the frame 1 is provided with a curved guide 7 concentric to the eye 4 and consisting, in the present instance, of a groove surrounding the upper inner surface of the eye. On this guide may turn an eye 8 which is connected at one end of the cross piece by an arm 9. This arrangement permits the rope 3 to serve as a pivot for the retaining member and at the same time to secure said retaining member in co-operative relation with the frame 1.

In order to facilitate the movement of the retaining member and at the same time to permit the latter to lie substantially within the lines of the frame 1, the frame is provided with a seat 10 on its upper surface, and the shoulders 11 formed at the ends of this seat, together with the wall of the guide 7, which forms a shoulder, serve to remove the strain on the cross piece from the rope.

To the end that accidental displacement of the cross piece will not take place during the use of the device, the cross piece has a recess 12 to receive the rope and this recess forms a shoulder 13 near the free end of the cross piece to co-operate with the rope and hold the retaining member against movement. Interlocking connection between the retaining device and the frame 1 may also be provided to prevent accidental displacement of the said retaining member. In this instance there is employed a locking device comprising a curved projection 14 on the under surface of the cross piece 6 adapted to pass over the frame and to enter the slot 2 to co-operate with the opposite walls of the latter. A locking means is also provided by the shoulders 15 at the ends of the guide 7 to co-operate with opposite sides of the retaining device.

In the use of the device, the rope 3 is placed about an object and the loop 5 intermediate the ends of the rope is formed and is passed through the slot 2 while the retaining device is in the position shown in Fig. 3, the latter is then swung between the arms of the loop and tension is applied to produce a binding action between the loop, the retaining device, and the frame 1, thus securing said rope against slipping.

A device constructed in accordance with this invention is very inexpensive to manufacture as it may be formed of but two pieces which do not require any assembling. The 5 parts are strong and durable and as they are not connected in any manner to each other, except by the rope, the device is not liable to breakage.

I claim as my invention:

- 19 1. In a device of the class described, the combination with a rope and a frame in the form of a loop at one end thereof, of a tongue spanning the loop provided with an eye at one end through which a portion of 20 the rope loosely passes permitting the rotation of the tongue about the rope itself as a pivot to bring the other end of the tongue into and out of coöperation with one side of the loop for the purposes set forth.
- 20 2. In a device of the class described, the combination with a buckle frame having an attaching portion for a flexible connector and having a buckle opening therein, of a tongue separate from the frame and movable relatively thereto, said tongue having a portion adapted to span the buckle opening and an attaching portion through which the flexible connector may be passed to constitute the sole means for holding the frame and tongue together.
- 30 3. In a device of the class described, the combination with a buckle frame having an attaching portion and also having a buckle opening therein, of a flexible connector secured to the attaching portion of the frame, and a tongue separate from the frame having a portion adapted to span the buckle opening and an attaching eye through which the connector is passed to constitute the sole 40 means for holding the frame and tongue together, the latter being movable on the connector into and out of operative relationship with the buckle opening.
- 45 4. In a device of the class described, the combination with a buckle frame having an attaching portion for a flexible connector and having a buckle opening therein, of a tongue separate from the frame having a portion adapted to span the buckle opening 50 and movable endwise across the latter, said tongue being provided with an attaching portion through which the flexible connector may be passed axially of the said movement of the tongue to provide a pivot for the latter.
- 55 5. In a device of the class described, the combination with a buckle frame having an attaching portion and having a buckle opening therein, and a flexible substantially 60 round connector secured to the attaching portion of a tongue separate from the frame embodying a hook arranged flatwise against the latter, said hook having an attaching eye through which the flexible connector is passed and a portion movable end-

wise across the opening in the frame on the connector as a pivot.

6. In a device of the class described, the combination with a buckle frame having a buckle opening therein and provided with an attaching eye, of a tongue separate from the frame embodying a hook arranged flatwise against the latter, said hook having an attaching eye in alignment with the eye of the buckle frame to turn about a member 70 passed through both eyes as an axis and being provided with a free end portion movable endwise across the opening in the frame by virtue of such turning movement.

7. In a device of the class described, the combination with a buckle frame having a long and a short loop, of a tongue separate from the frame comprising a hook shaped member arranged flatwise against the latter, said hook having an attaching eye in 80 alignment with the short loop of the buckle frame and a free outer end movable endwise about the eye as an axis transversely across the long loop thereof to span the same and a flexible connector secured to the short loop 90 of the buckle frame and passed through the eye of the tongue or hook.

8. In a device of the class described, the combination with a buckle frame having a buckle opening therein and provided with 95 an attaching portion, of a tongue separate from the frame embodying a bar pivotally movable endwise across the opening in the frame in a plane parallel with the latter to span said opening, said tongue being provided with an attaching portion at the center of its pivotal movement by means of which it and the frame may be held together solely by a rope coöperating with both attaching portions and serving as a pivot for 105 the tongue.

9. In a device of the class described, the combination with a frame having a slot and an eye at one end of the slot adapted to receive a rope, of a retaining device comprising a cross piece adapted to bridge the slot and an eye guided to turn about an axis coincident with the center of the eye of the frame.

10. In a device of the class described, the combination with a frame provided with a slot, with an eye at one end of the slot and with a curved guide concentric with the center of the eye, of a retaining device comprising a cross piece supported at one end 110 and adapted to bridge the slot and an eye movable on the guide of the frame.

11. In a device of the class described, the combination with a frame having a slot therein, an eye at one end of the slot and a 115 depressed seat on the upper surface of the frame, of a retaining device movable on the depressed seat, having an eye arranged to turn about an axis coincident with its center and the center of the eye of the frame, 130

and a cross piece supported at one end and adapted to bridge the slot.

12. In a device of the class described, the combination with a frame provided with a slot, with an eye at one end of the slot, and with a seat having a portion concentric with the center of the eye forming a guide, said seat having shoulders at its ends, and a retaining device pivotally movable on the guide, having a cross piece to bridge the slot and fitting against the shoulders when the cross piece bridges the slot.

13. The combination of a buckle plate having a long and a short loop, a rope fastened

in the short loop and looped through the long loop, a tongue pivoted on the rope adjacent to the short loop of the buckle plate and swinging across the long loop of the buckle plate and through the loop of the rope, said buckle plate being provided with a seat in the short loop for the pivot of said tongue and having stops on the long loop for said tongue.
